(57) **CLAIM**

The ornamental design for a fuel tank pylon cover, as shown and described.

DESCRIPTION

FIG. 1 is a perspective view of a fuel tank pylon cover in accordance with the present invention shown fitted on a fuel tank pylon;

FIG. 2 is a top view of the fuel tank pylon cover of FIG. 1; FIG. 3 is a right side elevational view of the fuel tank pylon cover of the invention, with the left side elevational view being a mirror image thereof;

FIG. 4 is a rear elevational view of the fuel tank pylon cover of the invention;

FIG. 5 is a front elevational view of the fuel tank pylon cover of the invention;

FIG. 6 is a lower right perspective view of the fuel tank pylon cover of the invention laying on a flat surface; and,

FIG. 7 is a bottom view of the fuel tank pylon cover of FIG. 1. The broken lines showing an optional upper rear cover pocket in FIGS. 1-4 and 6, a front strap in FIGS. 1-3 and 5-7, and front and rear underbody straps in FIG. 7 are for illustrative purposes only and form no part of the claimed invention.
